Primary Examiner — Catherine S Posthauer(74) *Attorney, Agent, or Firm* — Jeenam Park(57) **CLAIM**

The ornamental design for a mason jar sealer, as shown and described.

DESCRIPTION

FIG. 1 is a front, top and right side perspective view of a mason jar sealer, showing my new design;

FIG. 2 is a rear, bottom and left side perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

FIG. 9 is a front, top and right side perspective view of the design in a use status.

The broken lines are shown for the purpose of illustrating parts of the article as well as environmental subject matter of an exemplary jar. None of the broken lines form no part of the claimed design.

1 Claim, 9 Drawing Sheets(56)
